US00D886873S

(12) **United States Design Patent** (10) Patent No.: **US D886,873 S**
Büttner et al. (45) Date of Patent: **** Jun. 9, 2020**

(54) **COMPRESSOR WITH INTEGRATED ELECTROMOTOR**

(71) Applicant: **SIEMENS AKTIENGESELLSCHAFT**, München (DE)

(72) Inventors: **Klaus Büttner**, Hollstadt (DE); **Klaus Kirchner**, Ostheim (DE); **Matthias Warmuth**, Windshausen (DE)

(73) Assignee: **SIEMENS AKTIENGESELLSCHAFT**, München (DE)

(**) Term: **15 Years**

(21) Appl. No.: **29/649,651**

(22) Filed: **May 31, 2018**

(30) **Foreign Application Priority Data**

Dec. 4, 2017 (EM) 004534824

(51) LOC (12) Cl. **15-02**

(52) U.S. Cl.

USPC **D15/9**

(57) **CLAIM**

The ornamental design for a compressor with integrated electromotor, as shown and described.

DESCRIPTION

FIG. 1 is a front view of a first embodiment of a compressor with integrated electromotor, showing our new design; FIG. 2 is a rear view thereof; FIG. 3 is a top view thereof; FIG. 4 is a bottom view thereof; FIG. 5 is a right side view thereof; FIG. 6 is a left side view thereof; and, FIG. 7 is a front, top and right side perspective view thereof. The broken lines shown are included for the purpose of illustrating unclaimed subject matter and forms no part of the claimed design.

1 Claim, 7 Drawing Sheets
